ADJUSTABLE SINKER CAM ASSEMBLY FOR
KNITTING MACHINES

Maxwell P. Dodds, Laconia, N. H., assignor to
Scott & Williams, Incorporated, Laconia, N. H.,
a corporation of Massachusetts

Application April 29, 1949, Serial No. 90,494

12 Claims. (Cl. 66—14)

1

This invention relates to an adjustable sinker cam assembly for knitting machines particularly those of the superposed cylinder type in which the sinker control cams are located within the confines of one of the cylinders.

In machines of the superposed cylinder type the sinker control cams are relatively inaccessible, being located within one of the needle cylinders, and adjustment is made difficult. Such adjustments are desirable to take care of wear on the cams and to vary the depth of the knock-over movements of the sinkers for different size yarns. Furthermore, the removal and replacement of the sinkers which have become worn, broken, or otherwise damaged has been, in such machines, a difficult job involving usually removal of a cylinder and disturbance of any cam adjustments which may have previously been made.

One of the objects of the present invention is the provision of a sinker cam assembly which makes possible the fine adjustment of the sinker cams for the purpose of securing desired control of the sinker movements.

A further object of the invention relates to the provision of a sinker cam assembly which makes possible the removal and replacement of sinkers in a fashion which will not require the disassociation of the needle cylinders. In particular, such removal and replacement of sinkers is, in accordance with the invention, accomplished without disturbing the adjustment of the sinker cams.

These and other objects of the invention, particularly relating to details of construction and operation, will become apparent from the following description read in conjunction with the accompanying drawings, in which:

Figure 1 is a generally radial fragmentary section showing the sinker cams and associated parts assembled in the machine, the section being taken substantially on the broken surface the trace of which is indicated at 1—1 in Figure 2; and

Figure 2 is a plan view looking down on the assembly of Figure 1.

The lower needle cylinder of a superposed cylinder type of knitting machine is indicated at 2 and is provided with slots 4 for the reception of double-ended needles and lower controlling sliders, there being indicated at 6 the upper cylinder assembly which, as usual, is correspondingly slotted for the needles and their upper controlling sliders. These cylinders and various parts assembled therewith are conventional and

2

need not be particularly described. As indicated, only a limited space exists between the cylinders, rendering inaccessible the parts within the lower cylinder. As will presently appear, the construction which is provided permits removal and replacement of sinkers through this space between the cylinders, making it possible to effect such removal and replacement without removing the upper cylinder to provide any additional clearance.

A sinker ring of generally conventional type is indicated at 8, this sinker ring being slotted at 10 for the reception and guidance of the arcuate sinkers 12 which are conventional and which 15 move between the needles in the usual fashion in the knitting operations. These sinkers 12 are provided with butts 14.

A sinker cup 16 is externally threaded at its lower end, as indicated at 18, for the reception of 20 a nut 20. This nut is adapted to bear upon the inwardly directed flange 22 of the sinker sleeve 24. The outwardly directed flange 26 of the sinker cup 16 extends over the annular shoulder 28 of the sinker ring 8. Between the sinker ring 25 8 and the upper end of the sinker sleeve there is a thrust ring 30. The sinker ring 8 is keyed to the needle cylinder at 32.

The sinker cup 16 is provided with an annular shoulder at 25 so that when the nut 20 is tightened 30 the sinker cup 16 will be clamped to the inwardly directed flange 22 of the sinker sleeve. Under these conditions the sinker ring 8 will be free-running between the flange 26 and the thrust ring 30. The sinker sleeve 24, the sinker cup 16 and the nut 20 are stationary and supported by the frame at the lower end of the sinker sleeve 24 in conventional fashion.

The upper sinker cam ring 34 has a lower cam surface 36 cooperating with the sinker butts 14, 40 and the lower sinker cam ring 38 has a cam surface 40 also cooperating with these butts. The cam race which is provided between these cam surfaces is conventional and need not be described in detail. The cam surfaces impart the usual movements to the sinkers. Between the cam rings 34 and 38 there is located a spacer ring indicated at 42. This ring holds the two cam rings in fixed spaced relationship to each other. A plurality of slots 44, in this case three, 50 are provided in the sinker cup for the reception of keys 46 which are received in slots 45 in the spacer 42, slots 48 in the lower cam ring 38, and in slots 49 in the inner flange of the sinker sleeve 24, being held therein by screws 50 provided with lock washers 52. The slots 44, 48 and 49 asso-

ciated with one of these keys are accurately cut to fit the width of that key so as to maintain the keyed parts in accurately fixed circumferential relationship. The slots for the other keys may provide larger clearances with respect to the keys so as to avoid binding in assembly, these other keys being provided merely to limit upward movements of the sinker cams, as will be presently described.

Each of the keys 46 is provided with an outwardly directed ear 51 overlying an inwardly directed flange on the lower cam ring 38.

A group of sockets 54, six in number in the present machine, are provided in the sinker sleeve 24 for the reception of strong helical springs 56 which urge the lower cam ring 38 upwardly and with it the spacer 42 and the upper cam ring 34. Threaded into the sinker cup 16 are screws 58, three in number, which have rounded lower ends engaging within sockets 60 in the upper cam ring. Adjacent to these screws 58 are screws 62 which pass through countersunk holes in the sinker cup and are threaded into tapped openings 64 in the upper cam ring.

As will now be apparent the vertical position of the upper and lower cam rings and the spacer 42 as an assembled unit may be finely adjusted by adjustment of the screws 58, and the upper cam ring 34 may be locked in adjusted position by tightening of the screws 62 which also serve, in cooperation with the sockets 60, to maintain the proper circumferential position of the upper cam ring. The springs 56 urge the lower cam ring 38 upwardly to the position limited by the spacer 42, the lower cam ring being fixed circumferentially by the tight-fitting key 46.

It will be evident from the foregoing that the cam race receiving the sinker butts 14 may be very accurately positioned vertically and, depending upon its vertical position, will variably control the extent of the knock-over movements of the sinkers. A substantial range of adjustment is provided but, generally speaking, only a small range is required to provide adequate adjustment of the sinker butt race within the range. The strong springs 56 provide during operation a substantially rigid assembly after adjustment is effected.

The removal of the sinkers may be effected as follows:

As the nut 20 is freed the sinker cup 16 will be forced upwardly and with it the cam rings 34 and 38 and the spacer 42, by the action of the springs 56, the upward movement being limited by engagement of the inwardly directed flange of the cam ring 38 with the ears 51 of the keys 46. Under these conditions the lower cam surface 36 of the upper cam ring will, in the vicinity of the main feed position whereat the sinkers have their outermost position, clear the butts 14 of the sinkers so that they may be withdrawn by arcuate movements through the slots 18 and may be similarly replaced. Due to the fact that they may be thus removed and the fact that the sinker cup need not be lifted to any substantial extent it is unnecessary to remove the upper cylinder in effecting sinker replacement. It will be noted that the positioning of the parts as just mentioned does not disturb the adjusted and set position of the cam ring 34, and when the parts are restored to operating position by the tightening up of the nut 20 the cam race will be precisely located in its original adjusted position. Accordingly, the entire operation of replacing sinkers is greatly simplified as contrasted with the opera-

tion involved in the case of prior constructions which required very considerable dismantling of the major parts with the necessity for readjusting the sinker cams as a final step in putting the machine back into operation.

It will be clear that various details of construction involved may be modified without departing from the invention as defined in the following claims.

10. What is claimed is:

1. In a knitting machine of the superposed needle cylinder type, means mounting arcuate sinkers within one of said cylinders, means providing a cam race for butts on the sinkers, a member having an axially fixed position within the last mentioned cylinder, and means for axially adjusting said cam race providing means with respect to said member while maintaining the width of said cam race, so that movements of the sinkers relative to the needles may be varied.

15. 2. In a knitting machine of the superposed needle cylinder type, means mounting arcuate sinkers within one of said cylinders, means providing a cam race for butts on the sinkers, a member having an axially fixed position within the last mentioned cylinder, and means for axially adjusting said cam race providing means with respect to said member so that movements of the sinkers relative to the needles may be varied, said means for adjusting including a plurality of screws threaded into said member and bearing against said cam race providing means and means for binding the last mentioned means against the screws.

30. 3. In a knitting machine of the superposed needle cylinder type, means mounting arcuate sinkers within one of said cylinders, means providing a cam race for butts on the sinkers, a member having an axially fixed position within the last mentioned cylinder, said cam race providing means including elements providing upper and lower cams and spacing means for said elements, and means yieldingly urging said elements and spacing means together and to a predetermined position relative to said axially fixed member.

35. 4. In a knitting machine of the superposed needle cylinder type, means mounting arcuate sinkers within one of said cylinders, means providing a cam race for butts on the sinkers, a member having an axially fixed position within the last mentioned cylinder, said cam race providing means including elements providing upper and lower cams and spacing means for said elements, 40 means yieldingly urging said elements and spacing means together and to a predetermined position relative to said axially fixed member, and means for adjusting said predetermined position.

45. 5. In a knitting machine of the superposed needle cylinder type, means mounting arcuate sinkers within one of said cylinders, means providing a cam race for butts on the sinkers, a member having, normally, an axially fixed position within the last mentioned cylinder, means for locating said cam race providing means in predetermined position relative to said member, and means for effecting axial movement of said member and the cam race providing means therewith to locate said race in position to clear the sinker butts so that the sinkers may be removed from their mounting means by arcuate movements.

50. 6. In a knitting machine of the superposed needle cylinder type, means mounting arcuate sinkers within one of said cylinders, means pro-

viding a cam race for butts on the sinkers, a member having, normally, an axially fixed position within the last mentioned cylinder, means for locating said cam race providing means in predetermined position relative to said member, and spring means for effecting axial movement of said member and the cam race providing means therewith to locate said race in position to clear the sinker butts so that the sinkers may be removed from their mounting means by arcuate movements.

7. In a knitting machine of the superposed needle cylinder type, means mounting arcuate sinkers within one of said cylinders, means providing a cam race for butts on the sinkers, a member having, normally, an axially fixed position within the last mentioned cylinder, means for axially adjusting said cam race providing means relatively to said member, and means for effecting axial movement of said member and the cam race providing means therewith, without disturbing the relationship between the cam race providing means and said member, to locate said race in position to clear the sinker butts so that the sinkers may be removed from their mounting means by arcuate movements.

8. In a knitting machine of the superposed needle cylinder type, means mounting arcuate sinkers within one of said cylinders, means providing a cam race for butts on the sinkers, a member having, normally, an axially fixed position within the last mentioned cylinder, means for axially adjusting said cam race providing means relatively to said member, and spring means for effecting axial movement of said member and the cam race providing means therewith, without disturbing the relationship between the cam race providing means and said member, to locate said race in position to clear the sinker butts so that the sinkers may be removed from their mounting means by arcuate movements.

9. In a knitting machine of the superposed needle cylinder type, means mounting arcuate sinkers within one of said cylinders, means providing a cam race for butts on the sinkers, a member having, normally, an axially fixed position within the last mentioned cylinder, means for locating said cam race providing means in predetermined position relative to said member, means for effecting axial movement of said member and the cam race providing means therewith to locate said race in position to clear the sinker butts so that the sinkers may be removed from

their mounting means by arcuate movements, and means limiting axial movement of said member.

10. In a knitting machine of the superposed needle cylinder type, means mounting arcuate sinkers within one of said cylinders, means providing a cam race for butts on the sinkers, a member having, normally, an axially fixed position within the last mentioned cylinder, means for locating said cam race providing means in predetermined position relative to said member, spring means for effecting axial movement of said member and the cam race providing means therewith to locate said race in position to clear the sinker butts so that the sinkers may be removed from their mounting means by arcuate movements, and means limiting axial movement of said member.

11. In a knitting machine of the superposed needle cylinder type, a slotted member mounting arcuate sinkers within one of said cylinders, means providing a cam race for butts on the sinkers, said member having a portion extending radially inwardly beyond the sinkers, and means engaging said portion for fixing the axial position of said member, said engaging means having a running fit with said portion.

12. In a knitting machine of the superposed needle cylinder type, a slotted member mounting arcuate sinkers within one of said cylinders, means providing a cam race for butts on the sinkers, said member having a portion extending radially inwardly beyond the sinkers, means engaging said portion for fixing the axial position of said member, and means for axially adjusting said cam race providing means so that movements of the sinkers relative to the needles may be varied.

MAXWELL P. DODDS.
